(57) **CLAIM**

The ornamental design for a battery module, as shown and described.

DESCRIPTION

FIG. 1 is a first perspective view of a battery module showing our new design;

FIG. 2 is a second perspective view thereof;

FIG. 3 is a front elevation view thereof;

FIG. 4 is a rear elevation view thereof;

FIG. 5 is a side view thereof;

FIG. 6 is an opposite side view thereof;

FIG. 7 is a top plan view thereof; and,

FIG. 8 is a bottom plan view thereof.

The broken lines depict portions of the battery module that form no part of the claimed design.
